N. J., a corporation of New Jersey

Application June 10, 1929, Serial No. 369,634

13 Claims. (Cl. 197—126)

This invention relates to manifolding machines, and more particularly, to that type of machine wherein the worksheets are supported on the platen to receive writing either by hand or by typewriting mechanism.

An object of the present invention is to provide improved means for facilitating the advancement of the worksheets over the platen predetermined extents or form-lengths when the worksheets on the platen have been written upon and it is desired to place fresh portions thereof into writing position. The means provided by the present invention for this purpose comprises one or more intercepting pins at the delivery side of the platen located in the path of movement of the pile of worksheets so that when apertures in the worksheets reach the pins, the latter project into the apertures and intercept further withdrawal of the pile of worksheets. Resilient means are also provided for urging the worksheets toward the pins and for holding them on the pins, and this resilient means is so arranged that when the end of the pile is lifted by hand, the resilient means yields and permits the pins to be disengaged from the apertures to permit the strips to be advanced until the next set of apertures is reached.

An important feature of the present invention is the provision of an attachment for typewriting machines of the Elliott-Fisher type which permits the paper-intercepting pins and the resilient means above referred to, to be mounted on the typewriter quickly and with ease and without making any changes in the typewriter construction other than to substitute one form of tear-off knife for another.

Other features and advantages will herein-after appear.

In the accompanying drawings—

Figure 1 is a top plan view of the platen and frame therefor of an Elliott-Fisher typewriter, showing the present invention attached thereto.

Fig. 2 is a longitudinal section through the platen, showing the parts in the positions they occupy during the writing operation.

Fig. 3 is a view similar to Fig. 2, but showing the positions of the parts during the beginning of the advancement of the pile of strips over the platen.

Fig. 4 is a perspective view of the modified form of tear-off knife used with the device of the present invention.

Fig. 5 is a perspective view of the attachment of the present invention.

56 The embodiment of the present invention

herein disclosed is shown as applied to an Elliott-Fisher typewriting machine in which there is a platen 10 supported in a frame 11 and adapted to support in writing position a pile of worksheet strips 12 which may be led from any suitable 5 source of supply, as, for instance, rolls 13 supported on shafts or rods 14 mounted in the frame 11. The pile of worksheet strips 12 is led from the rolls 13 over separator bars 15 to the receiving end of the platen and from thence 10 extends forwardly over the platen to the delivery end 16 thereof after being interleaved with carbon strips 17 indicated in dotted lines in Fig. 1 and adapted to be supported by longitudinally extending shafts or rods 18, one at each side of 15 the frame 11.

The side members of the frame 11 are connected by a front transverse frame member 19, a rear transverse frame member or bar 20, see Fig. 1, and an intermediate frame member 21. 20 The front bar 19 is a casting of the form indicated in Figs. 1, 2 and 3, and is provided with two rearwardly extending platen-supporting lugs 22 to receive pins 23 depending from the front end of the flat platen 10 which occupies that 25 portion of the platen frame between the side members thereof and the frame bars 19 and 21.

Below the lugs 22, the pins 23 are encircled by springs 25 which hold the platen down, washers 26 being interposed between the springs and the 30 heads of the pins 26. The openings in the lugs 22 are slightly larger than the pins to permit slight movement of the platen at its front end which is occasioned by the dropping of the rear end of the platen away from rear platen-stops 27, 35 carried by the bar 21 by means of blocks 28 cut to receive the bar 21 and retained in their adjusted positions by the set screws 29.

Coacting with the upper edge of the front bar 19 is a tear-off knife and clamp 30 overlying 40 the leading edges of the worksheets and extended entirely across the front edge of the platen and in advance thereof. The knife and clamp 30 and the upper edge of the front bar 19 is angularly disposed with relation to the platen 45 to more securely hold the worksheets in position and the knife has a front cutting edge 31 against which the worksheets may be drawn and severed after being pulled forwardly beyond the writing area of the platen to separate a set of 50 written forms from that following.

It should be noted that the front bar 19 at its center has arcuate depressions 32 extending to a point directly below the tear-off knife which facilitates the gripping by hand of the front or 55

leading edges of the forms which are located under the clamp and tear-off knife 30.

The tear-off knife 30 is carried by swinging arms 33 fixed to a shaft 34 to which are also fixed 5 rearwardly extending bifurcated arms 35 and depending retracting arms 36 urged in one direction by retracting springs 37. The springs 37 are connected at their rear ends to platen-raising or elevating levers 38 of bell-crank form carried by 10 a transverse shaft 39 below the rear end of the platen. At the ends of the levers 38, opposite the points of attachment of the springs 37, are mounted platen-supporting rollers 40 which engage the underside of the platen and support the rear end thereof in elevated position against the rear platen stop and paper clamp 27 under normal or writing conditions.

Mounted to swing from the shaft 39 and having 20 a pin-and-slot connection 41 with the arms 35 are a pair of levers 42 connected intermediate their ends by a transverse bar 43 on which is provided a bail 44 having its front ends extended under the shaft 34. The rear end of the bail 44 is connected as by a chain 45 to a treadle or other 25 operating means adapted to be controlled by the user of the machine. When the chain is pulled down, the bail 44 will be pulled with it with the shaft 34 acting as a fulcrum and the bar 43 serving to apply power to the arms 42 for the purpose 30 of depressing the latter, rocking the shaft 34 through the medium of the arms 35 and causing the cut-off bar and clamp 30 to be elevated as the arms 33 are swung upwardly to permit the operator to grasp the leading edges of the work- 35 strips preparatory to drawing the same forwardly.

For the purposes of the present invention, it is immaterial whether or not the platen 10 is allowed to drop preparatory to pulling the sheets forwardly, since the workstrips are not necessarily clamped between the platen and the front and rear clamps 30 and 27. In the type of machine disclosed, however, the platen does descend, and for a more complete understanding of the 40 features described, particularly the last referred 45 to, attention is called to the patent to Foothorap No. 1,687,332, patented October 9th, 1928.

The device of the present invention is adapted 50 to be employed with worksheet strips having apertures 46 provided near the foot of each form, so that through the medium of these apertures 55 the amount of withdrawal of the strips may be limited and accurately gaged to bring the lines of severance 47, which separate the strips into form-lengths, just below the cutting edge 31 of the tear-off bar at each paper-withdrawing operation.

The device of the present invention comprises 60 a plate 48 adapted to be supported upon the upper edge of the front bar 19 and having downwardly bent lugs 49 adapted to engage the rear upper margin of the bar 19 to lie between the surface thereof and the end of the platen and to hold the plate against moving in paper-withdrawing direction. The plate 48 also has forward 65 downwardly extending arms 50 adapted to lie on the front surface 51 of the vertical portion of the bar 19, and thus by joint action of the arms 50 and the lugs 49, the plate 48 is prevented from moving either forwardly or backwardly on the bar 19.

To hold the plate 48 down on the upper edge 70 of the bar, each of the arms 50 is provided with a hook-shaped clamp 52 adapted to conform to the shape of the bar 19 and having hooks 53 75 which embrace the forward edge of the bar 19

and engage the under surface 54 of the bar. The hook-shaped clamps 52 are made separate from the arms 50 so that the plate 48 may be slid in a vertical plane over the top of the bar 19 after the clamps have been removed and then the 5 clamps 52 may be secured in place by means of screws 55 threaded in the arms 50 and a spacing block 56 welded thereto. In order to permit the device to be mounted on any machine of the type 10 for which it is designed regardless of minor variations occurring in the manufacture thereof, such as the thickness of the casting 19, the hook-shaped clamps 52 are provided with slots 57 through which the fastening screws 55 pass and which permit up-and-down adjustment of the 15 hook-shaped clamps to proper position before the screws 55 are tightened.

To intercept the withdrawal of the worksheet strips, the plate 48 is provided with a pair of vertically extending pins or fingers 58 of such size, 20 shape and position as to enter the holes 46 in the worksheet strips. They may be separate pins placed in the plate 48 or they may, as shown, be made integral with the plate being merely fingers struck up from the plate. The pins are 25 slightly narrower than the diameter of the holes in the strips so that the holes 46 in the worksheets will fit over them loosely when the holes reach the pins in the paper-withdrawing operation. 30

To hold the worksheets down with the fingers 58 projecting upwardly through the holes 46 in the normal or writing positions of the worksheets, the present invention provides a resilient member 35 in the form of a relatively long coil spring 59 each end of which is anchored in an angularly supporting member 60 secured to the plate 48. The spring 59 is of such dimensions and the angular members 60 are so placed that the lower edge of the spring is normally below the tops of the 40 fingers 58 and thus, as shown in Fig. 2, the worksheets are held down on the pins.

The spring 59 may be provided with a tube 61, 45 preferably made of rigid material, thru which it passes and which acts as a sheath and causes the part of the spring enclosed thereby to move up and down bodily when initiating the withdrawal 50 of the strips and when forcing the strips down toward the platen.

The spring 59 yields to permit the portion 50 thereof which is within the tube 61 to rise above the tops of the fingers 58, as shown in Fig. 3, when the leading edges of the worksheet strips 55 are raised by hand and this permits the holes 46 in the worksheets to be free of the fingers 58 so that they may be drawn forwardly to bring a fresh portion of the worksheets to writing position, after the tear-off knife 30 has been moved from its worksheet clamping position shown in Fig. 2 to its inoperative position shown in Fig. 3. 60 As the paper-withdrawing operation continues, the direction of pull on the leading edges of the strips becomes more nearly horizontal and thus the spring 59 is permitted to urge the strips down- 65 wardly.

This, however, it cannot do beyond causing the surface of the lowermost worksheet to engage the tops of the pins 58, until the next succeeding set of holes 46 approaches the pins 58. And, when 70 this occurs, the spring 59 causing the tube 61 to bear downwardly upon the pile of worksheets causes the strips to descend and the apertures 46 and pins 58 to be engaged and prevent further advancement of the strips. The operator then, 75

by releasing a treadle or other operating means connected to the chain 45, allows the clamp and tear-off knife 30 to again engage the pile of strips and securely clamp them in place. This having been done, the writing forms of the worksheet strips are drawn upwardly against the cutting edge 31 of the knife 30 to sever them from the succeeding portions of the strips.

Since the worksheet strips may be substantially narrower than the platen 10 and thus not be guided by any of the usual means provided on the platen for the purpose, the present invention provides a pair of lateral guides 62 carried directly by the plate 48 of the attachment. In the form of the invention herein illustrated, these lateral guides are formed by cutting out and shaping strips from the material of the plate itself and bending them so as to produce a horizontal portion 63 lying above the pile of worksheet sheets and a vertical portion 64 forming a guide surface for the side edges of the worksheet strips of the pile.

The lateral guides 62 hold the respective strips of the pile in lateral registration with the apertures 64 aligned, and are so positioned on the plate that they maintain the pile of strips with the apertures 46 in line with the pins 58.

As shown in Fig. 5, the horizontal member 63 of the lateral guide is located in a plane slightly above the tops of the fingers 58 and that these horizontal members are located in a vertical plane slightly behind the vertical plane in which the fingers lie so that the lateral guides do not in any way interfere with the lifting movement 35 of the pile of webs which is necessary to free the pile from the fingers 58.

As above stated, the present invention provides a cut-off knife 30 which is slightly different from that usually supplied with the machine for 40 which the attachment described above is designed. This knife is identical with the knife usually supplied except that the portion 65 between the ends 66 is made much narrower. This narrow portion is provided so that the knife may, 45 in swinging down from the position shown in Fig. 3 to that shown in Fig. 2, clear the fingers 58 and the spring 59 and its sheath 61.

It will thus be seen that the present invention provides an attachment which may be easily and 50 quickly attached to existing forms of manifolding machines such as the typewriter shown herein and which includes means for intercepting paper-withdrawal so as to regulate the advancement of the worksheet strips form-length intervals, and 55 that the sole moving part of the attachment is the spring 59 with its sheath 61.

Variations and modifications may be made within the scope of this invention and portions of the improvements may be used without others.

Having thus described the invention, what is claimed as new and for which it is desired to obtain Letters Patent, is:—

1. An attachment for manifolding machines having a platen for supporting in writing position a plurality of continuous strips each having apertures at form-length intervals, and having a cross-bar at the delivery side of the platen, said attachment including a plate; strip-intercepting pins carried by the plate and adapted to enter 65 said apertures; and hook-shaped brackets for clamping the plate to the cross-bar, said brackets being adjustably connected to said plate.

2. An attachment for manifolding machines having a platen for supporting in writing position a plurality of continuous strips each having

apertures at form-length intervals, and having a cross-bar at the delivery side of the platen, said attachment including a plate; strip-intercepting pins carried by the plate and adapted to enter 5 said apertures; ears on the plate adapted to engage one side of the cross-bar and lie between the cross-bar and the platen for holding the plate against movement in paper-withdrawal direction; and arms on said plate engaging the other side of the cross-bar which in conjunction 10 with said ears holds the plate against movement horizontally relative to the cross-bar.

3. An attachment for manifolding machines having a platen for supporting in writing position a plurality of continuous strips each having 15 apertures at form-length intervals, and having a cross-bar at the delivery side of the platen, said attachment including a plate; strip-intercepting pins carried by the plate and adapted to enter 20 said apertures; ears on the plate adapted to engage one side of the cross-bar and lie between the cross-bar and the platen for holding the plate against movement in paper-withdrawal direction; arms on said plate engaging the other 25 side of the cross-bar which in conjunction with said ears holds the plate against movement horizontally relative to the cross-bar; and hook-shaped brackets connected to said arms to hold the plate against vertical movement relative to 30 the cross-bar.

4. An attachment for manifolding machines having a platen for supporting a plurality of continuous strips in writing position, each strip having apertures at form-length intervals, said attachment including a plate adapted to be secured adjacent the platen in the path of travel 35 of the strips; strip-intercepting pins carried by the plate and adapted to enter said apertures to regulate strip-withdrawal; and resilient means for urging the strips toward the pins to cause 40 the pins to enter the apertures when the latter reach the pins.

5. An attachment for manifolding machines having a platen for supporting a plurality of continuous strips in writing position, each strip having 45 apertures at form-length intervals, said attachment including a plate adapted to be secured adjacent the platen in the path of travel of the strips; strip-intercepting pins carried by the plate and adapted to enter said apertures to regulate 50 strip-withdrawal; and a spring secured at opposite ends of the plate and extending close to the pins for normally urging the strips toward the pins to cause pins to enter the apertures in the strips when the apertures reach the pins. 55

6. An attachment for manifolding machines having a platen for supporting a plurality of continuous strips in writing position, each strip having apertures at form-length intervals, said attachment including a plate adapted to be secured adjacent the platen in the path of travel 60 of the strips; strip-intercepting pins carried by the plate and adapted to enter said apertures to regulate strip-withdrawal; a coil spring secured at opposite ends of the plate and extending close 65 to the pins for normally urging the strips toward the pins to cause the pins to enter the apertures in the strips when the apertures reach the pins; and a protecting sheath surrounding the spring.

7. An attachment for manifolding machines 70 having a platen for supporting a plurality of continuous strips in writing position, each strip having apertures at form-length intervals, said attachment including a plate adapted to be secured adjacent the platen in the path of travel 75

- of the strips; strip-intercepting pins carried by the plate and adapted to enter said apertures to regulate strip-withdrawal; arms secured at each end of the plate; and a coil spring having its 5 ends anchored in said arms and extending close to the pins for normally urging the strips toward the pins to cause the pins to enter the apertures in the strips when the apertures reach the pins.
8. An attachment for manifolding machines 10 having a platen for supporting a plurality of continuous strips in writing position, each strip having apertures at form-length intervals, said attachment including a plate adapted to be secured adjacent the platen in the path of travel of the 15 strips; strip-intercepting pins carried by the plate and adapted to enter said apertures to regulate strip-withdrawal; and resilient means for urging the strips toward the pins to cause the pins to enter the apertures when the latter reach the 20 pins, said resilient means extending across the strips and being adapted to yield when the strips are lifted to remove the apertures in the strips from the pins.
9. An attachment for manifolding machines 25 having a platen for supporting a plurality of continuous strips in writing position, each strip having apertures at form-length intervals, said attachment including a plate adapted to be secured adjacent the platen in the path of travel of the strips; a pair of pins formed integral with the plate and projecting upwardly therefrom adapted to enter said apertures to regulate strip-withdrawal; lateral guides formed integral with the plate for engaging the side edges of the strips 30 to maintain the strips in such a position that the apertures thereof are in line with the pins; a pair of arms at each end of the plate; a coil spring extending across the strips and having its ends anchored in said arms, said coil spring being located close to the pins and normally urging the strips toward the pins to cause the pins to enter the apertures in the strips when the apertures reach the pins, said spring adapted to yield to permit the strips to be lifted to remove the pins 35 from the apertures; and a sheath surrounding the spring and adapted to cause the portion of the spring above the strips to rise and fall bodily in its movement under the influence of the strips when the latter are raised from the pins.
10. In a manifolding machine, a platen for supporting a plurality of continuous strips in writing position, each strip having apertures at form-length intervals; means for regulating with- 40
- drawal of the strips comprising a pair of non-receding pins located at the delivery side of the platen and adapted to engage the apertures in the strips and intercept progress of the strips in their direction of withdrawal; and means for normally urging the strips toward said pins and for normally holding the strips with the pins projecting into said apertures, said means being releasable under the influence of the paper to permit disengagement of the pins and the apertures 45 5 10 when initiating the withdrawal of the strips and merely by manually grasping and moving the strips in one direction.
11. In a manifolding machine, in combination, a strip controlling pin positioned for engagement 15 in apertures of a continuous traveler record strip, and a strip guiding tensioned coil spring positioned adjacent to said pin.
12. An attachment for a manifolding machine equipped with a platen for supporting in writing 20 position continuous strips having strip-controlling apertures spaced therealong, comprising, in combination, a securing device for securing said attachment to the manifolding machine adjacent to the platen in the path of travel of the strips, 25 whereby the attachment may be secured in operative position on the machine or removed as a unit, said attachment including a plate, a strip-controlling pin carried by said plate and adapted to enter said apertures to control strip withdrawal, a strip-guiding member carried by said attachment and including an elongated strip-engaging member extending transversely of the strip path adjacent to said pin, and resilient means cooperating with said strip-engaging member for urging the strips toward the pin to cause said pin to enter the apertures when the latter are moved forwardly into alignment with the pin. 30 35
13. An attachment for manifolding machines having a platen for supporting a plurality of continuous strips in writing position, each strip having apertures at form-length intervals, said attachment including a plate adapted to be secured adjacent the platen in the path of travel of the strips; strip-intercepting pins carried by 40 the plate and adapted to enter said apertures to regulate strip-withdrawal; and resilient means for urging the strips toward the pins to cause the pins to enter the apertures when the latter reach the pins, said resilient means extending across 45 the strips and being adapted to yield transversely of the plane of the strip path. 50

HEZEKIAH W. CARROLL, JR.
